UNITED STATES PATENT OFFICE.

JOHN K. WICK, OF OAKLAND, CALIFORNIA.

TRACTOR TRUCK.

Application filed August 20, 1923. Serial No. 658,282.

My invention is an improved tractor.

The object of my invention is to provide a tractor in which the forward ends of the tracks are movable vertically, with no tipping of the track.

Another object is to improve the supporting shoe on the lower reach of the track.

Further objects and advantages will be described in the following detailed explanation.

In the annexed drawing in which my invention is illustrated.

Fig. 1 is a side view of my tractor.

Fig. 2 is a front view of the same.

Fig. 3 is a sectional view taken on the line 3—3 of Fig. 2.

Fig. 4 is a sectional view taken on the line 4—4 of Fig. 1.

Fig. 5 is a sectional view taken on the line 5—5 of Fig. 1.

Referring more particularly to the drawing: My tractor comprises a main frame 1 and track frames 2—2 positioned at either side thereof. Journaled at the rear end of the frames 2—2 are the drive sprockets 3, and at the forward end are journaled the idler sprockets, over which the tread 4^a is adapted to travel.

The sprockets 3 are secured to shafts 5 which are journaled in suitable bearings in the frames 1 and 2, and are driven in the usual manner for this type of tractor; thus the frames 2 are pivoted upon the shafts 5, as will be further described.

The frames 2—2 are supported at their forward ends upon a pair of bars 6 and 7, which are pivoted at their center upon pins 8 and 9 respectively. These pins are secured in a yoke 10 which is fastened to the frame 1 by the bar 11. The bars 6 and 7 are each pivoted at their ends to the frames 2, and these bars are spaced a distance apart so that as they swing on the pins 8 and 9, the ends of said bars will remain in a vertical line, thus the frames 2—2 are not tipped and the strains upon the tracks 4^a and sprockets 4, are thus reduced.

The tread 4^a is formed of a plurality of links 12, which are pivoted together, and in each of which a roller 13 is journaled. The rollers 13 have central rings 14 formed upon them, the purpose of which will be

further described. The sprockets 3 and 4 are suitably slotted as at 15 to receive the rings 14.

Supporting brackets 16 are secured to the frames 2—2 and support the upper reach of the tread 4^a.

Supporting shoes 17 are secured to the frames 2, the rear and forward ends of which extend to approximately the center line of the sprockets 3 and 4 respectively, thus supporting the entire lower reach of the tread 4^a, and reducing the strain thereupon. The tread is thus supported throughout its entire length while in contact with the ground. The shoe 17 is formed in two parallel pieces and thus straddles the sprockets 3 and 4. The ring 14 travels in the space between the two halves of the shoe 17 and thus prevents the tread 4^a from sliding off of the said shoe.

A plurality of springs 18 are positioned between the shoes 17 and the frames 2, against which said shoe bears, thus forming a yieldable base against which the tread 4^a operates. Under light loads the springs 18 force the tread 4^a downwardly to approximately the position shown in dotted lines in Fig. 1 thus facilitating the turning of the tractor.

A suitable truck body 19 is positioned on the tractor.

Having described my invention, I claim:

1. A tractor comprising a main frame, track frames positioned on either side of said main frame, a drive sprocket and an idler sprocket journaled in said track frames, a track encircling said drive sprocket and said idler sprocket, said track being formed of a plurality of links, rollers journaled in said links, a ring formed on each roller, and supporting shoes secured to said track frames against which said track is adapted to bear, said shoe extending to approximately the center line of said sprockets, said shoes being split longitudinally, said rings being adapted to ride in the split.

2. A tractor comprising a main frame, a track frame positioned at each side of the main frame, a plurality of sprocket wheels journaled in said track frames, tracks encircling said sprocket wheels, said tracks being formed of a plurality of links, a roller

journaled in each of said links, a ring formed at the midsection of each of said rollers, supporting shoes secured to said track frames to bear against said rollers, said shoes terminating adjacent the vertical diameters of said sprocket wheels, said shoes being split longitudinally to receive said rings, and springs interposed between said track frames and said supporting shoes. In testimony whereof I affix my signature.

JOHN K. WICK.
